(57) **CLAIM**

The ornamental design for an emergency safety night light, as shown and described.

DESCRIPTION

FIG. 1 is a front elevation view of the emergency safety night light according to the present design.

FIG. 2 is a left side view thereof, with the right side being a mirror image.

FIG. 3 is a back elevation view thereof; and,

FIG. 4 is a top, plan view thereof, with the bottom being a mirror image.

The portions of the emergency safety night light shown in broken lines form no part of the claimed design.
